(57) **CLAIM**

The ornamental design for a beauty lamp, as shown and described.

DESCRIPTION

FIG. 1 is a front, right and top perspective view of a beauty lamp, showing my new design;

FIG. 2 is a rear, left and bottom perspective view thereof;

FIG. 3 is a front, left and top perspective view thereof;

FIG. 4 is a front view thereof;

FIG. 5 is a rear view thereof;

FIG. 6 is a left side view thereof;

FIG. 7 is a right side view thereof;

FIG. 8 is a top plan view thereof;

FIG. 9 is a bottom plan view thereof;

FIG. 10 is an enlarged view of the portion labeled “10” in FIG. 1 thereof;

FIG. 11 is an enlarged view of the portion labeled “11” in FIG. 1 thereof;

FIG. 12 is an enlarged view of the portion labeled “12” in FIG. 1 thereof;

FIG. 13 is an enlarged view of the portion labeled “13” in FIG. 1 thereof; and,

FIG. 14 is an enlarged view of the portion labeled “14” in FIG. 1 thereof.

The broken lines shown in the drawings illustrate portions of the beauty lamp that form no part of the claimed design. The dot-dash broken lines shown in FIGS. 1 and 10-14 depict the bounds of the enlarged views and form no part of the claimed design.

1 Claim, 14 Drawing Sheets
